Primary Examiner — Keli L Hill(74) *Attorney, Agent, or Firm* — Baker & Hostetler LLP(57) **CLAIM**

I claim the ornamental design for an aerosol can, as shown and described.

DESCRIPTION

FIG. 1 is a top view of an aerosol can according to a first embodiment of our new design;

FIG. 2 is a bottom view thereof; FIG. 3 is a front view thereof, the front view being identical to the rear view, the left side view, and the right side view;

FIG. 4 is a front cross-sectional view thereof according to line 4-4 shown in FIG. 1;

FIG. 5 is a top perspective thereof;

FIG. 6 is a top view of an aerosol can according to a second embodiment of our new design;

FIG. 7 is a bottom view thereof;

FIG. 8 is a front view thereof, the front view being identical to the rear view, the left side view, and the right side view;

FIG. 9 is a top view of an aerosol can according to a third embodiment of our new design;

FIG. 10 is a bottom view thereof; and,

FIG. 11 is a front view thereof, the front view being identical to the rear view, the left side view, and the right side view.

Broken lines shown in the Drawings represent unclaimed portions of the aerosol can and form no part of the claimed design.
